FURNACE DAMPER CONTROL

George W. Folk, Kalamazoo, Mich.

Application April 8, 1935, Serial No. 15,163

10 Claims. (Cl. 236—16)

The main objects of this invention are:

First, to provide an improved furnace damper control which is especially well adapted for controlling the operation of furnaces of the hot air type.

Second, to provide an improved differentially operable thermostatically controlled mechanical movement.

Third, to provide improved means for manually adjusting the effective relation between the dampers and the heat responsive apparatus.

Fourth, to provide in a furnace damper control an improved thermostat structure, particularly well adapted for the purpose.

Fifth, to provide a furnace damper control which is simple and economical in its parts and very efficient and effective in operation.

Objects relating to details and economies of my invention will appear from the description to follow. The invention is defined and pointed out in the claims.

Preferred embodiments of my invention are illustrated in the accompanying drawings, in which:

Fig. 1 is a fragmentary perspective view of a hot air heating system embodying features of my invention.

Fig. 2 is an enlarged fragmentary view partially in side elevation and mainly in vertical longitudinal section through the bonnet of the furnace.

Fig. 3 is an enlarged view partially in section on a line corresponding to line 3—3 of Fig. 2.

Fig. 4 is a fragmentary view partially in side elevation and partially in section on line 4—4 of Fig. 3.

Fig. 5 is an enlarged fragmentary view in side elevation of the manually adjustable means for changing the effective relation between the heat responsive apparatus and the dampers.

Fig. 6 is an enlarged fragmentary view in front elevation of the manually operable end of the Bowden tube control means.

Fig. 7 is a fragmentary view mainly in side elevation and partially in section of a modification.

Fig. 8 is an enlarged fragmentary view partially in side elevation and partially in section on line 8—8 of Fig. 9.

Fig. 9 is a fragmentary view in transverse vertical section on line 9—9 of Fig. 8.

In the embodiment of my invention illustrated in Figs. 1 to 6 inclusive of the drawings, 1 is a hot air furnace having a draft damper 2 and a flue damper 3 for controlling the fire and consequently the heat delivered by the furnace through the top or bonnet 4 thereof, the heat transfer medium being in this case air. Inasmuch as furnaces of this general type are well known to those skilled in the art, it is not necessary to set forth here details of the structure or operation thereof. It is sufficient to say that the heat delivered by the furnace is increased by opening the draft damper and closing the check damper, the generated heat being reduced by closing the draft damper and opening the check damper.

In the top 4 of the furnace I dispose an elongated heat responsive element or member 5 in the form of a channel opening downwardly in 10 the path of the heating medium traversing the furnace top, the channel being provided with longitudinal slots 6 therein and integral cross webs 7 provided with aligned holes 8 for a rod 9. The heat responsive element 5 preferably has a 15 relatively high coefficient of linear expansion while the rod 9 has a relatively low or negligible coefficient of linear expansion. The materials which I prefer to use for this purpose are an aluminum alloy for the channel and a steel alloy 20 for the rod.

The outer end of the rod 9 is fixed to the outer end of the element 5 by means of nuts 10 threaded to the rod and engaging the end web 11 of the element. To support or permit free movement of the end of the elements 5 and 9, I provide a supporting bearing 12 in a wall casing 13 mounted on the bonnet. The extreme outer end 14 of the rod projects into the wall casing 13 and rests on the bearing 12.

The inner end of the element 5 is provided with an integral furnace bonnet escutcheon 15 having spaced side plates 16 substantially in line with the sides of the element. The escutcheon is secured to the wall of the bonnet 4, an opening 17 being provided in such wall for the passage of the element 5. The escutcheon is provided with a bore 18 constituting a bearing for the cross head 19 on the inner end of the rod 9. Thus, the cross head 19 is free to move in the 40 escutcheon in accordance with the expansion and contraction of the heat responsive element 5. This movement is translated to a pair of damper control levers 20 and 21 through links 22 and 23, the levers being pivoted together and 45 to the plates 16 at 24.

The damper control lever 20 is connected to the draft damper 2 by means including a cable 25 and a pulley 26. The damper control lever 21 is connected to the check damper 3 by means including a cable 27 and pulleys 28 and 29. The pulley 29 is suspended by a cable 30 which is connected to the fuel supply door 31 of the furnace and is guided by pulleys 32, 33, and 34, the pulley 34 being arranged above the pulley 29. 55 With this arrangement, the opening of the fuel supply door 31 results in the closing of the check damper 3.

The pulleys 26 and 28 are carried at the opposite ends of a pivoted hanger 35, the hanger 60

being supported by a bracket 36 and having a crank 37 connected to one end of a Bowden tube wire 38. The other end of the wire 38 is provided with a knob 39 adapted to be manually manipulated to adjust the position of the hanger 35. One end of the casing 41 is connected to the bracket 36, the other end of the casing being connected to a bracket 40. The part of the bracket 40 at the rear of the knob 39 is marked or calibrated for coaction with the knob to indicate the degree of heat which will result from various settings thereof. The stem 39 connecting the knob to the wire 38 of the Bowden tube is also marked off in units of length by numbers for coaction with the marks on the back of the bracket 40. Thus, the degree of heat desired may be accurately determined by adjusting the knob 39.

Movement of the hanger 35 about its pivot results in moving the dampers oppositely through the pulleys 26 and 28 by changing the effective lengths of the cables 25 and 27, the effective length of the cable 25 being shortened to open the check damper 2 and the effective length of the cable 27 being increased to close the check damper 3 when the knob 39 is depressed to swing the hanger 35 counterclockwise, as viewed in Fig. 1. The Bowden tube control means acts to hold the hanger in adjusted position, the heat responsive apparatus then acting to maintain constant the delivery of that heat for which the control is adjusted.

A tendency of the furnace to deliver more heat, for example, is counteracted by the differential expansion of the heat responsive element 5 relative to the rod 9, which results in a movement of the damper control levers 20 and 21 acting to close the draft damper 2 and open the check damper 3. Thus, the heat responsive apparatus automatically maintains the desired delivery of heat by the furnace.

Referring to the modification illustrated by Figs. 7, 8 and 9 of the drawings, the effective relation between the dampers and rod is manually controlled by means of a crank 45 pivoted to the end plates 16 of the escutcheon at 46, the damper control levers 20 and 21 being pivoted to a pin 47 carried by the crank 45 for movement in arcuate slots 48 in the plates 16. Otherwise, the damper control apparatus is substantially the same as that disclosed and described above in connection with Figs. 1 to 6, inclusive.

In the modification, the crank 45 is adjusted through and is held in adjusted position by the Bowden tube control means, the position of the crank governing the effective relation between the cross head 19 and the pivot pin 47. The Bowden tube control means acts through the crank 45 to hold the pivot pin 47 fixed in adjusted position relative to the cross head 19. The heat responsive apparatus thereupon functions to maintain constant the delivery of that heat for which the control is adjusted, as pointed out above. Because of simplicity and fewer parts, I prefer to use the structure of the modification for manually adjusting the effective relation between the heat responsive apparatus and the dampers controlled thereby.

From the foregoing description of my invention, it will be apparent to those skilled in the art that I provide a furnace damper control which is not only simple and economical in its parts, but which is very efficient and effective for the purpose intended, the control being readily adjusted and acting to automatically

function in accordance with such adjustment. The control results in a great saving in fuel and is quite desirable from a health standpoint in dwellings. Features of my invention are, of course, applicable to heating systems other than those using furnaces of the hot air type. I have in mind hot water and steam heating systems.

I have illustrated and described my improvements in embodiments which I find very practical. I have not attempted to illustrate or describe other embodiments or adaptations as it is believed this disclosure will enable those skilled in the art to embody or adapt my improvements as may be desired.

Although I have shown and described certain specific embodiments of my invention, I am fully aware that many modifications thereof are possible. My invention is therefore not to be restricted except insofar as is necessitated by the prior art and by the spirit of the appended claims.

Having thus described my invention, what I claim as new and desire to secure by Letters Patent, is:

1. In a furnace damper control, the combination of a heat responsive member of elongated channel shape having integral cross webs in longitudinally spaced relation and longitudinal slots in the top thereof and means for anchoring one end of the member in the top of a furnace, the other end being free to move longitudinally of the member relative to the furnace top, the member being adapted to be disposed with the channel opening downwardly in the path of the heating medium traversing the furnace top, said cross webs having aligned holes, a rod arranged through said holes and having one end fixed to the free end of said member, the coefficient of expansion of said rod being negligible compared to that of said heat responsive member, damper control levers pivoted to the fixed end of said heat responsive member, and means connecting the other end of said rod to said levers so that the movement of the free end of said member due to the longitudinal contraction and expansion of said member is transmitted to said damper control levers to cause adjustment of the latter to regulate and maintain substantially constant the heat delivered by the furnace through its top, said connecting means comprising a pair of links pivoted to said levers and said rod.

2. In a furnace damper control, the combination of a heat responsive member of elongated channel shape having cross webs in longitudinally spaced relation, said cross webs having aligned holes, a rod arranged through said holes and having one end fixed to the corresponding end of said member, the coefficient of expansion of said rod being small compared to that of said member, damper control levers pivoted to the other end of said member, and means positively connecting the other end of said rod to said levers so that the longitudinal contraction and expansion of said member is transmitted to said damper control levers to cause movement of the latter, said connecting means comprising a pair of links pivoted to said levers and said rod.

3. In a furnace damper control, the combination of a heat responsive thermostatic element of elongated channel cross section adapted to be positioned face downwardly and having longitudinal slots at the top thereof and cross webs in longitudinally spaced relation, said thermostatic element having at one end a supporting bracket adapted for attachment to a casing of

- a hot air furnace to support the element in horizontal relation above the top of a furnace body, said bracket comprising an escutcheon plate and a pair of spaced flanges, a rod slidably arranged 5 in said cross webs and secured to the outer end of said thermostatic element, the thermostatic element having a relatively high coefficient of expansion as compared to said rod, control levers disposed in opposed relation and pivotally 10 mounted between said bracket flanges, and links connecting said rod to said levers whereby the levers are positively moved oppositely through the contraction and expansion of said thermostatic element acting upon said rod.
- 15 4. In a furnace damper control, the combination of a heat responsive thermostatic element of elongated channel cross section adapted to be positioned face downwardly and having longitudinal slots at the top thereof and cross webs in 20 longitudinally spaced relation, a rod slidably arranged in said cross webs and secured to the outer end of said thermostatic element, the thermostatic element having a relatively high coefficient of expansion as compared to said rod, 25 control levers disposed in opposed relation, and links positively connecting said rod to said levers whereby the levers are moved oppositely through the contraction and expansion of said thermostatic element acting upon said rod.
- 30 5. In a furnace damper control, the combination of an elongated channel having longitudinal slots therein and cross webs provided with aligned openings, the channel having a relatively high coefficient of linear expansion, a rod extending 35 through said openings, the rod having a relatively low coefficient of linear expansion, means fixing one end of said rod to the corresponding end of said channel, a cross head on the other end of said rod, the channel having a furnace 40 bonnet escutcheon provided with spaced side plates in line with the sides of the channel, said escutcheon being provided with a bore constituting a bearing for said cross head, damper control levers pivotally connected to said side 45 plates for movement therebetween, links connecting said cross head to said levers, and manually controlled means for adjusting the effective relation between said rod and the dampers controlled thereby through said levers.
- 50 6. In a furnace damper control, the combination of an elongated member having a relatively high coefficient of linear expansion, an elongated member having a relatively low coefficient of linear expansion, means connecting corresponding ends of said members, a cross head on the other end of one member, damper control levers pivotally connected to said other member, links 55 positively connecting said cross head to said levers, whereby expansion and contraction of said member will be transmitted to said levers, and manually controlled means for adjusting the effective relation between said cross head and the dampers controlled thereby through said levers, said means comprising a Bowden tube, and a crank, the position of which is adjusted 60 through and held in adjusted position by said Bowden tube, the position of the crank governing the effective relation between said rod and the dampers.
- 65 7. In a furnace damper control, the combination of an elongated heat responsive element terminating at one end in parallel side plates having opposed arcuate slots therein, said element being in the form of a downwardly opening channel, an adjustable crank pivoted to said side plates and having a cross pin extending through 5 said slots for movement therein with the crank, damper control levers pivoted to said pin for movement between said side plates, a rod extending through said element for differential movement longitudinally of said heat responsive element, the outer end of the element being fixed to the outer end of the rod, links connecting said rod to said damper control levers so that the expansion and contraction of said element is translated to said levers, and means for manually adjusting said crank to change the position of said pin relative to said rod, said means comprising a Bowden tube.
- 10 8. In a furnace damper control, the combination of an elongated heat responsive element terminating at one end in parallel side plates having opposed arcuate slots therein, an adjustable crank pivoted to said side plates and having a cross pin extending through said slots for movement therein with the crank, damper control levers pivoted to said pin for movement between said side plates, a rod extending through said element for differential movement longitudinally of said heat responsive element, the outer end of the element being fixed to the outer end of the rod, links connecting said rod to said damper control levers so that the expansion and contraction of said element is translated to said levers, and means for manually adjusting said crank to change the position of said pin relative to said rod.
- 15 9. In a furnace damper control, the combination of a heat responsive element provided with parallel end plates, an adjustable crank pivoted to said end plates and having a cross pin, damper control levers pivoted to said pin for differential movement between said end plates, links connecting said element to said damper control levers so that the expansion or contraction of said element is translated to said levers, and means for manually adjusting said crank to change the position of said pin relative to said connecting means, said adjusting means comprising a Bowden tube wire.
- 20 10. In a furnace damper control, the combination of a heat responsive member, means for anchoring one end of the member in the top of a furnace, the other end being free to move longitudinally of the member relative to the furnace top, a rod having one end fixed to the free end of said member, the coefficient of expansion of said rod being negligible compared to that of said heat responsive member, damper control levers pivoted to the fixed end of said heat responsive member, and means connecting the other end of said rod to said levers so that the movement of the free end of said member due to the longitudinal contraction and expansion of said member is transmitted to said damper control levers to cause adjustment of the latter to regulate and maintain substantially constant the heat delivered by the furnace through its top, said connecting means comprising a pair of links pivoted to said levers and said rod.
